UNITED STATES PATENT OFFICE.

HARRY T. PORTER AND GEORGE H. BEAUMONT, OF CLEVELAND, OHIO,
ASSIGNORS OF ONE-THIRD TO WILLARD T. MOORE, OF CLEVELAND,
OHIO.

BUCKET-DUMPING DEVICE FOR STEAM-SHOVELS.

SPECIFICATION forming part of Letters Patent No. 702,473, dated June 17, 1902.

Application filed February 5, 1902. Serial No. 92,663. (No model.)

To all whom it may concern:

Be it known that we, HARRY T. PORTER and GEORGE H. BEAUMONT, citizens of the United States, and residents of Cleveland, county of 5 Cuyahoga, and State of Ohio, have invented a new and useful Improvement in Bucket-Dumping Devices for Steam-Shovels, of which the following is a specification, the principle of the invention being herein explained and 10 the best mode in which we have contemplated applying that principle, so as to distinguish it from other inventions.

Our invention relates to the dipper-discharging means of steam-shovels or similar 15 machines, in which a dipper mounted upon a movable arm is employed and which embodies tripping mechanism for controlling the operation of discharging the contents of the dipper. Heretofore in machines of this character two operators have been necessary, the one for controlling the movements of the dipper-arm and the other for effecting the operation of the tripping mechanism for controlling the discharging operation. For this purpose a line has been attached to the tripping mechanism, one end of which was held by the 20 dumping-operator, who when the dipper reached a location above the point at which it was desired to discharge the dipper's contents pulled the line, and so effected the discharge. The tripping mechanism is of necessity of a character such as to prevent premature discharge, and in order to fulfil this requirement the parts are so arranged as to require a very considerable pull upon the line 25 to effect the actuation of such mechanism and the consequent discharge or dumping operation. The great amount of effort required has hence made it unfeasible for the operator 30 to controlling the movements of the dipper-arm to also discharge or dump the contents of the dipper and effect the most economical operation of the machine. Such operation of the dipper-arm involves the manipulation of three or four levers, so that the operator who 35 would be required to also discharge would after having brought the dipper to the proper point be obliged to bring it to a dead stop for the period which he would require to grasp

and pull the tripping-line. It has hence been 50 found more expedient and economical to employ two operators, as above mentioned. The construction necessitated by the conditions surrounding the use of these machines has further made it necessary and advisable to 55 place one operator upon one side of the machine and the other upon the other side, so as not to interfere with each other's operation, in which position communication or signaling between the two has been difficult or entirely impossible. The two operators were hence entirely independent of one another and neither could have any direct knowledge of the intentions or operations of the other. It hence frequently occurs that the dumping 60 operation is caused to take place either prematurely or too late, thereby depositing the contents of the bucket in undesirable places. In the case of loading cars with ore from piles this lack of coördination between the 65 two operators results in the spilling of large quantities of ore alongside the track, all of which must be subsequently removed by hand, returned to the pile, and handled again. Where several shovels are at work simultaneously, the spilling involves the expenditure 70 of a large amount of labor and consequently of expense.

The object of our invention is to obtain a 75 perfect coördination in effecting these two operations, and this we effect by providing means whereby one operator can effect both.

Said invention consists of means herein-after fully described, and specifically set forth 80 in the claims.

The annexed drawings and the following description set forth in detail certain mechanism embodying the invention, such disclosed means constituting but one of various 85 mechanical forms in which the principle of the invention may be used.

In said annexed drawings, Figure I represents a side elevation of one type of steam-shovel at present employed, showing a device embodying our invention applied thereto. 90 Fig. II represents an enlarged detail elevation of the shovel or dipper-arm, showing said invention applied thereto. Figs. III and IV

represent a cross-sectional and plan view, respectively, of a cylinder and piston forming a part of said invention. Fig. V represents a cross-sectional view of a three-way valve 5 employed in connection with our said invention.

Upon the upper side of the dipper-arm and intermediately of its ends is secured a cylinder A, in which is located a movable piston 10 A', Fig. III, to which is attached a piston-rod a. In each end of the cylinder intermediately of the piston and such ends is located a spring a' and a'', which serves to take up the motion of the piston at the ends of its 15 stroke and prevent injury to the mechanism by reason of impact of the piston which would otherwise occur. The rear end of said cylinder is provided with a relief-opening a³, to which is attached an L-nipple a⁴, whose outer 20 end is covered with a screen a⁵ for preventing the ingress of extraneous substances.

A port a⁶, Fig. IV, is formed in the front of the cylinder, to which is attached a pipe a⁷, which in turn connects with a flexible conduit a⁸. The other end of the conduit connects with a supply-pipe a⁹, secured to the frame F, which communicates with an air-compressor in the engine-house. In this pipe and in close proximity to the levers B, which 25 control the movements of the dipper-arm, is a three-way valve a¹⁰, provided with a suitable handle, whereby the compressed air may be admitted into the cylinder in front of the piston or the compressed air already in the 30 cylinder may be exhausted therefrom.

The forward end of the piston-rod is connected with the tripping-lever C by means of a flexible connection, such as a chain D, the length of such chain being such as is required 40 to operate lever C to trip when the piston is actuated to move to the rear end of the cylinder.

The dipper-arm consists in that form of steam-shovel to which our invention is illustrated as being applied of an outer tubular portion E and an inner slidable and rotatable stem E', to the outer end of which the dipper is secured. This stem is provided with angular recesses e, into which clamp-bolts e' project to prevent longitudinal movement, but which permit a movement about the axis of the dipper-arm. Such axial movement is necessary in the operation of this type of steam-shovel in order to allow the dipper to assume 50 an angular position when it meets with unusual resistance. The flexible chain D hence offers no obstacle to such axial movement, and the dipper may be given substantially any desired angular position without rendering the cylinder and piston inoperative.

In operating the above-described mechanism the dipper-arm is manipulated by the operator by means of the levers B, the tripping mechanism being set so as to lock the 60 gate in the dipper-bottom. Such tripping mechanism forms no part of our present invention and may be of any desired construc-

tion which is caused to lock by gravity, such construction being well known to those skilled in the art. The flexible conduit permits the movement of the dipper-arm to take place without disturbing the connection of the cylinder with the source of compressed air and supply-pipe. When the dipper reaches its required position, the air is admitted by 70 the operator controlling the dipper-arm in front of the piston and the latter moved thereby toward the back of the cylinder, such movement being accompanied by the actuation of the tripping mechanism and the consequent discharge of the contents of the dipper. The three-way valve being in close proximity to the operator, the manipulation of said valve may be effected by him without interfering with his manipulation of the levers B. To further facilitate this operation, we provide a weight W, which is secured to the end of the handle of the valve, Fig. I, and maintains the valve in a position in which the cylinder is exhausting. A rope R is secured to the handle, passes up over a pulley P, falls in a loop, and has its ends secured to a convenient point p. By merely grasping and pulling the loop the valve is turned so as to admit air into the cylinder and by releasing it the air is exhausted. After the dumping operation the valve is so turned as to permit the compressed air to be exhausted from the cylinder. The dipper and dipper-arm being subsequently lowered for its next 85 load, as shown in dotted lines in Fig. I, the piston reassumes its original position, thereby slackening the chain and permitting the tripping mechanism to relock the dipper-gate. 95

Other modes of applying the principle of 105 our invention may be employed instead of the one explained, change being made as regards the mechanism herein disclosed, provided the means stated by any one of the following claims or the equivalent of such stated 110 means be employed.

We therefore particularly point out and distinctly claim as our invention—

1. In a steam-shovel, the combination of a dipper, a movable dipper-arm, tripping mechanism for controlling the discharge of the dipper, and means mounted upon such arm for operating such mechanism. 115

2. In a steam-shovel, the combination of a dipper, a movable dipper-arm, tripping mechanism for controlling the discharge of the dipper, and a motor cylinder and piston mounted upon such arm connected with and adapted to operate said mechanism. 120

3. In a steam-shovel, the combination of a dipper, a movable dipper-arm, tripping mechanism for controlling the discharge of the dipper, a motor cylinder and piston mounted upon said arm connected with and adapted to operate said mechanism, and a flexible 125 pneumatic conduit intermediate of said cylinder and the shovel-frame. 130

4. In a steam-shovel, the combination of a dipper, a movable dipper-arm having said dip-

per secured thereto so as to be movable substantially about the axis of said arm, a motor cylinder and piston mounted upon the latter, tripping mechanism for controlling the discharge of the dipper, and a flexible connection intermediate of said cylinder and piston, and said tripping mechanism.

Signed by us this 22d day of January, 1902.

HARRY T. PORTER.
GEO. H. BEAUMONT.
